UNITED STATES PATENT OFFICE.

COLIN CAMPBELL, OF NEWARK, NEW JERSEY, ASSIGNOR TO JOSEPH S. MUNDY, OF SAME PLACE.

FRICITION-DRUM.

SPECIFICATION forming part of Letters Patent No. 645,163, dated March 13, 1900.

Application filed April 28, 1898. Serial No. 679,056. (No model.)

To all whom it may concern:

Be it known that I, COLIN CAMPBELL, a citizen of the United States, and a resident of Newark, in the county of Essex and State of New Jersey, have invented certain new and useful Improvements in Friction-Drums, of which the following is a specification.

This invention relates to improvements in friction-drums, the object being to produce such a device in which the friction between the drum and the mechanism for engaging it with the friction device will be reduced to a minimum. In the drums now in use it frequently occurs that at this point the parts become highly heated, and it has been found in practice that oil or lubricants will not effectually prevent this heating. By my invention I seek to overcome this defect; and to this end my invention consists of the certain combination and arrangement of parts hereinafter more fully pointed out and described in the claims.

Referring to the accompanying drawings of my invention, Figure 1 is a top plan view, partly in section, of a friction-drum embodying my invention. Fig. 2 is a section taken on the line 2 2 of Fig. 1. Fig. 3 is a section taken on the line 3 3 of Fig. 1, and Fig. 4 illustrates in detail the form of means for engaging the drum with the friction device which I prefer to employ.

In the drawings, A is the drum, loosely mounted on the constantly-rotating shaft B, which rotates in the journals C and D. The shaft B carries with it the gear-wheel E, which meshes with the pinion F, mounted on shaft G, which is rotated by an engine, motor, or other source of power. The gear E is provided with the friction-cone H, which engages 40 with the drum A.

To the side of the journal C is secured a claw or bracket I, through which extends the operating-shaft J. The bracket I is formed on its inner face with a cam I', and the shaft J carries a coöperating cam J'. The end of the shaft J bears against the rear of the two-armed thrust-pin L, which passes through the journal C on either side of the shaft B, and the ends thereof engage a collar M, which is 45 free to move horizontally on the shaft B, as shown. To the operating-shaft is fixed a suit-

able operating-handle K, by means of which the shaft J is rotated. Upon rotation of the shaft the cams I' and J' coöperate to force the thrust-pin L inwardly, thereby moving the 55 collar M. The drum A is provided with a suitable collar N, which rotates therewith when the drum is in engagement with the friction device. Between the collars M and N are located a series of hardened-steel balls O, which are confined in a circular runway formed on the adjacent sides of said collars M and N, as shown in Figs. 1 and 3. Heretofore when these collars have been in contact with each other and the friction resulting when the drum was 60 in operation was often sufficient to cause an intense heating of the collars. It has been found in practice that oil or other lubricants do not effectually prevent this heating, for the reason that the oil is driven from between 65 the collars by the rapid rotation of the drum. By my invention I obviate this difficulty and produce a friction-drum which is easily and quickly controlled by the hand-lever K, and in which there is no appreciable heating of 70 the parts. A spring P is preferably provided, as shown, to throw the drum out of engagement with the friction device when the hand-lever K is moved to release the drum.

Although I prefer to use the coöperating 80 cams I' and J' as the operating means in my device, I may employ the means shown in Fig. 4. In this figure the bracket I is interiorly screw-threaded, and the operating-shaft J² is screw-threaded to engage the screw-threads 85 of the bracket. The handle K is fixed to the outer end of the shaft J² and is operated in the same manner as before described.

What I claim as new, and desire to secure by Letters Patent, is—

1. The combination in a hoisting-machine 90 of a shaft, a friction-drum loosely mounted upon said shaft, a friction device for engaging the drum, a two-armed thrust-pin, a collar adapted to be moved horizontally on the 95 shaft by said pin, and an operating means bearing against the rear of said pin for moving the latter to engage the drum with the friction device.

2. The combination in a hoisting-machine 100 of a shaft, a friction-drum loosely mounted on said shaft, a two-armed thrust-pin, a col-

lar adapted to be moved horizontally on the shaft by said pin, an operating means bearing against the rear of said pin for moving it to engage the drum with the friction device and a series of balls located between said collar and drum, substantially as described.

3. The combination in a hoisting-machine of a bearing, a shaft, a friction-drum loosely mounted on said shaft, a two-armed thrust-pin passing through said bearing, a bracket secured to said bearing and straddling said pin, an operating-lever, a cam moved by said lever, a cam formed upon the bearing of said lever, said cams operating to force the thrust-pin forwardly to engage the drum with the friction device, and a series of balls located between said collar and the drum, substantially as described.

4. The combination in a hoisting-machine of a shaft, a friction-drum loosely mounted upon said shaft, an operating-pin comprising a body portion and two arms formed integrally therewith, a collar adapted to be moved on the shaft, by said pin, said arms engaging the rear of said collar, a bearing for the shaft, a cam formed on said bearing, an operating-pin, a cam carried by said operating-pin, and an operating-lever rotating said operating-pin, substantially as described.

Signed by me at Newark, in the county of Essex and State of New Jersey, this 8th day of February, 1898.

COLIN CAMPBELL.
